FISHING ROD HANDLE

William D. Carlson, 200 Stevenson Road,
New Haven, Conn. 06515

Filed May 18, 1972, Ser. No. 254,837

Term of patent 14 years

Int. Cl. D22—05

U.S. Cl. D22—23

FIG. 1 is a side elevational view of my fishing rod handle, the opposite side elevational view being identical;

FIG. 2 is an end view looking from the left edge of the drawing;

FIG. 3 is an end view looking from the right edge of the drawing;

FIG. 4 is a cross-sectional view taken along the line 4—4 of FIG. 1; and

FIG. 5 is a cross-sectional view taken along line 5—5 of FIG. 4.

I claim:

The ornamental design for a fishing rod handle, substantially as shown and described.
